(57) CLAIM

The ornamental design for a bingo ink marker bottle, as shown and described.

DESCRIPTION

FIG. 1 is an exploded perspective view of a bingo ink marker bottle showing our new design with a cap thereof;

FIG. 2 is a top plan view thereof;

FIG. 3 is a bottom plan view thereof;

FIG. 4 is a right side elevational view thereof, the left side elevational view being a mirror image thereof;

FIG. 5 is a front elevational view thereof;

FIG. 6 is a rear elevational view thereof; and,

FIG. 7 is a cross-sectional view thereof along line 7—7 of FIG. 6.

The part shown in broken lines in FIG. 1 is shown for illustrative purposes only and forms no part of the claimed design.
